17, 1970. This application Mar. 2, 1972, Ser. No.
231,450

Claims priority, application Switzerland Mar. 23, 1970

Term of patent 14 years

Int. Cl. D28—03

U.S. Cl. D95—3 A

FIG. 2

FIG. 1

FIG. 3

FIG. 4

FIG. 5

FIG. 6

FIG. 7

FIG. 8

FIG. 1 is a perspective view of a dry shaver showing my new design, with cover in place;

FIG. 2 is a front elevational view with the cover in exploded relationship with the shaver;

FIG. 3 is a rear elevational view with the cover omitted;

FIG. 4 is a front elevational view with the cover omitted;

FIG. 5 is a left side elevational view with the cover omitted;

FIG. 6 is a right side elevational view with the cover omitted;

FIG. 7 is a top plan view with the cover omitted;

FIG. 8 is a bottom plan view.

This application is a continuation of my application Ser. No. D. 25,034, filed Sept. 17, 1970, now abandoned.

I claim:

The ornamental design for a dry shaver, as shown.
